UNITED STATES PATENT OFFICE.

RANSOM K. BURT, OF FRANKFORT, MICHIGAN, ASSIGNOR OF ONE-HALF TO
N. AUGUSTUS PARKER, OF SAME PLACE.

HAME ATTACHMENT.

SPECIFICATION forming part of Letters Patent No. 309,129, dated December 9, 1884.

Application filed May 12, 1884. (No model.)

To all whom it may concern:

Be it known that I, RANSOM K. BURT, a citizen of the United States, residing at Frankfort, Benzie county, Michigan, have invented 5 a new and useful device or improvement in a combined hame-tug and breast-strap coupling attachment to a hame of a double harness, of which the following is a specification.

My invention relates to a tug and holdback 10 attachment for harness; and the novelty consists in the construction, arrangement, and adaptation of parts, as will be more fully hereinafter set forth, and specifically pointed out in the claims.

15 The essential object of the invention is to provide an attachment for hames which shall carry the holdback-ring and tug or draft attachment which shall be inexpensive of manufacture, efficient and desirable in service, and 20 easily applied to the wood-work of ordinary hames, and one which will embrace and be secured to the said wood-work without puncturing it or diminishing its strength.

The invention is illustrated in the accompanying drawings, which form a part of this 25 specification, and in which Figure 1 is a perspective view of a portion of a hame with my improvement attached, and Fig. 2 is a cross-section taken at about the line $x x$ of Fig. 1.

30 Referring to the drawings, similar letters refer to similar parts in both figures.

H designates an ordinary hame, and A the body of my improved attachment, having a re-enforced portion, as A'. This body A is 35 formed with extensions E, which have a bearing in and are secured to the outer side of the

hame by nails or screws aa , and an embracing-plate, F, which is preferably countersunk and secured to the inner face of the hame. The body has formed upon it in any suitable manner the tug or draft-staple D, and the re-enforced portion A' is perforated to receive the shank of the eye B, that carries the ring C. The eye B is projected through the body and is headed down upon the inner side before the 45 same is secured to the hame, and the head, when the body is in position, bears upon the forward face of the hame. By this construction the hame is not weakened by the attachment, and the whole may readily be applied 50 with very little labor. The re-enforced portion A' supports or resists the strain of the eye B.

Having thus described my invention, what I claim as new, and desire to secure by Letters 55 Patent, is—

1. In combination with the body A, having re-enforced portion A', and formed to embrace the wood of the hame, as set forth, the eye B, headed upon the inner side of the body, and 60 the ring C, as specified.

2. The hame attachment described, consisting of the body A, having re-enforced portion A' and embracing plates E and F, the eye B, projected through the re-enforced portion and 65 headed upon the inner face of the body, the draft-staple D, and ring C, all arranged, combined, and serving as set forth.

RANSOM K. BURT.
